SHOE

Sidney Sandler, 310 E. 44th St., Manhattan, N.Y.

Filed Oct. 24, 1962, Ser. No. 72,241

Term of patent 7 years

(Cl. D7—7)

FIG. 1 is a side elevational view of a shoe showing my new design;

FIGS. 2, 3 and 4 are top plan, rear elevational, and front elevational views, respectively, of said shoe; and

FIG. 5 is a side elevational view of another embodiment of the design wherein the heel is more elevated and the side bevels on the heel are shallower.

The dominant features of my design reside in the portions shown in full lines.

I claim:

The ornamental design for a shoe, substantially as shown and described.
